United States Patent Office.

T. F. MANTEY, OF NEW ORLEANS, LOUISIANA.

Letters Patent No. 78,302, dated May 26, 1868.

IMPROVED EXTENSION-LADDER.

The Schedule referred to in these Letters Patent and making part of the same.

TO ALL WHOM IT MAY CONCERN:

Be it known that I, T. F. MANTEY, of New Orleans, in the parish of Orleans, and State of Louisiana, have invented new and useful Improvements in Extension-Ladders; and I do hereby declare that the following is a full, clear, and exact description thereof, which will enable those skilled in the art to make and use the same, reference being had to the accompanying drawings, forming part of this specification, in which—

Figure 1 is a plan view of the actuating-mechanism of the ladder.

Figure 2 is a side elevation of the ladder and wagon bearing it.

Similar letters of reference indicate corresponding parts.

This invention refers to a ladder for a fire-escape and other uses.

It consists of a chair, elevated by a system of pivoted lattice-bars, in combination with the elevating and adjusting-mechanism, with certain improvements perfecting the whole, as will hereinafter be more fully set forth.

In the drawings, the pivoted extension-lattice is shown at A.

These are constructed upon the principle familiarly known as "lazy-tongs."

The chair, B, is attached by a curved slotted plate, L, as shown, the pivot *i* traversing in the slot *g*, when the ladder is raised or lowered, by which action the chair is held horizontally.

When the lower bars, C, are drawn together, the lattice-bars composing the whole system are likewise drawn more vertical, which accomplishes the elevation of the chair B, as will be obvious.

H is a crank, for turning the screw G, which accomplishes the drawing in or pushing out of the bars C, for the said screw works in hollow screws in the cross-bars E, as shown.

The lower bars C are mounted on a stout bar, N, having bearings P in the stout standards D, as shown.

These standards rise from a cross-plate, Q, which has a central hole, by which it is hung on the central pintle-base R, rising from the centre of the bed-plate S, resting on and bolted to the carriage-frame T, the latter being mounted on the wheels U, which constitute the means of transportation of the apparatus.

The axle-trees are bent, so as to bring the bed-plate and actuating-mechanism near the ground, for the purpose of conferring stability upon the whole machine.

The extension *q* of the cross-plate Q is furnished with a pin, *r*, which bears upon the bed-plate S, as shown, thus relieving the pintle from any strain, and providing a firmer base for the superstructure.

A tongue, M, extending from the cross-plate Q, and forming part of the same, serves to turn the ladder upon the pintle-base R, and to steady the same, if requisite, the pin *r* bearing upon the plate S, when the ladder is turned upon the pintle-base or held steadily in one position.

Two bars, *k*, projecting from the cross-plate Q, are connected with the standards D by a brace-rod, *e*, as shown, for the purpose of strengthening the standards D.

Anchoring-bars, K, are pivoted to the frames T, and are provided at their outer end with a crank-screw, J, for the purpose of holding the whole apparatus firmly, when the same is located at any point for use.

Chains or cords, *b*, attached to the lower extremities of the bars C, as shown, are wound up on winches *v v*.

These winches are placed just above the cross-plate Q, and have bearings in projecting arms attached to the said cross-plate, as shown.

These winches are turned by handles *h*.

The purpose of this last-described attachment is to adjust the ladder at any desired angle from the perpendicular, or to bring the same to a vertical position, which can be accomplished by turning the handles *h* in the proper corresponding directions.

In operating this ladder, it is drawn to the desired locality, and firmly secured to the ground by the arm K and crank-screw J, before described.

The crank, H, is then turned, and the chair elevated.

The proper angle of deflection is obtained by winding the chain *b* on one winch, and unwinding it from the other.

By means of the tongue *M*, the ladder is turned on its pintle, so as to bring the chair in the proper position. Pawls, *m*, catch into the teeth of the ratchet-wheels *n* of the winches, and hold the same at any desired angle. This machine can thus be employed as a fire-escape, or as a ladder for any common purpose, or it will be found useful for military reconnaissance.

In practice it is composed of iron, and the sections of the extension-lattice are pivoted by bolts and nuts, in the manner shown, the central pivot-bolts extending across and connecting the two sides of the extension-lattice.

The bars of the lattice project beyond the pivots, as shown at *w*. Their extremities, *u*, are bent to form a stop, which comes in contact with the adjacent bar, when the ladder is fully extended, whereby the lattice-bars are held more firmly. This invention is simple and durable, and will be found in practice to fully accomplish the object for which it is intended.

I claim as new, and desire to secure by Letters Patent—

1. The winches *v*, in combination with the extension-lattice *A* and chains *b*, for the purpose of adjusting the lattice; when elevated by the screw *G*, at any desired angle, as herein shown and described.
2. The crank-screw *J* and bar *K*, in combination with the frame *T* and extension-lattice *A*, all substantially as and for the purpose shown and described.
3. The combination of the pintle-base *R*, extension-lattice *A*, adjustable plate *Q*, having the projection *q*, bearing the pin *r* and tongue *M*, all arranged and operating as described for the purpose specified.
